GARDEN TOOL

Earl J. Kilgore, Kenvir, Ky.

Application March 13, 1952, Serial No. 18,865

Term of patent 14 years

(Cl. D35—2)

To all whom it may concern:

Be it known that I, Earl J. Kilgore, a citizen of the United States, residing at Kenvir, county of Harlan, and State of Kentucky, have invented a new, original, and ornamental Design for a Garden Tool, of which the following is a specification, reference being had to the accompanying drawing, forming part thereof.

Figure 1 is a perspective view of a garden tool, showing my new design,

Figure 2 is an end elevational view thereof, and Figure 3 is a side elevational view.

I claim:

The ornamental design for a garden tool, as shown.

EARL J. KILGORE.
